UNITED STATES PATENT OFFICE.

CHARLES BARNUM, OF REDWOOD FALLS, MINNESOTA.

SHOCK-FORMING ATTACHMENT FOR GRAIN-BINDERS.

1,093,906.

Specification of Letters Patent.

Patented Apr. 21, 1914.

Application filed February 20, 1913. Serial No. 749,687.

To all whom it may concern:

Be it known that I, CHARLES BARNUM, a citizen of the United States, residing at Redwood Falls, in the county of Redwood 5 and State of Minnesota, have invented certain new and useful Improvements in Shock-Forming Attachments for Grain-Binders; and I do declare the following to be a full, clear, and exact description of the invention, such as will enable others skilled in the art to which it appertains to make and use the same.

This invention relates to improvements in shock forming attachments for grain 10 binders.

One object of the invention is to provide an attachment of this character adapted to receive the bundles of grain as they are bound and discharged from the machine 15 and which when a sufficient number of bundles have been received will automatically discharge the bundles on end and in the form of shocks.

Another object is to provide an attachment of this character which will be simple, strong and durable in construction, efficient, reliable and entirely automatic in 20 operation and which may be readily applied to binders now in use.

With these and other objects in view, the invention consists of certain novel features of construction, and the combination and arrangement of parts as will be more fully described and claimed.

In the accompanying drawings: Figure 1 is a rear view of a portion of a grain binder showing my improved shocking attachment applied thereto and in position to receive the bundles discharged from the machine;

Fig. 2 is a top plan view of the attachment and a portion of the binder to which the same is applied; Fig. 3 is a side view of the attachment with the parts in position for receiving the shocks discharged from the 40 machine; Fig. 4 is a similar view with the parts in dumped position for placing the bundles on the ground in the form of shocks; Fig. 5 is a rear view of the attachment showing the parts in dumped position;

Fig. 6 is an enlarged side view of a portion of the attachment showing the position of the parts when the carrier is dumped and the bundles discharged therefrom and illustrating the manner in which the carrier retracting mechanism is thrown into 50 55

gear for bringing the carrier back to a normal position; Fig. 7 is a horizontal sectional view taken on the line 7—7 of Fig. 6; Fig. 8 is a detail perspective view of a portion of the attachment illustrating the means for holding the carrier in a normal position for receiving the shocks discharged from the machine.

My improved bundle forming attachment comprises a supporting frame consisting of a horizontally disposed bar or beam 1 which is secured by suitable brackets to the upper portion of the bundle conveyer frame F of the binder. The bar 1 has fixed thereto intermediate its ends a right angular laterally projecting horizontal carrier supporting bar 2 on the outer end of which is secured a depending vertically disposed arm 3, said arm being held rigid by a curved brace bar 4 connected thereto and to the bar 2 as shown. The bar 1 is preferably formed of channel iron while the bar 2 and arm 3 are preferably constructed of gas pipe or tubular metal bars. The frame when thus constructed is firmly supported by a cable 5 which is connected to the outer end of the bar 2 and extends inwardly and upwardly over a forked brace or prop 6 secured to the channel iron bar 1. Said cable after passing from the prop 6 extends downwardly across the machine and has its opposite end suitably secured to the frame of the machine at its side thereof as shown.

Revolvably mounted in suitable bearings 7 on the bar 1 is a main drive shaft 8 having on one end a sprocket gear 9 which is connected by a short sprocket chain 10 with a sprocket gear 11 on the adjacent end of the upper conveyer shaft S of the machine, said conveyer shaft being geared to and driven by the ground wheel of the machine in the usual manner. Fixed on the shaft 8 intermediate its ends is a bevel gear pinion 12 with which is engaged a bevel gear 13 on the end of a right angularly disposed laterally projecting power transmitting shaft 14 which is revolvably mounted in suitable bearings on the bar 2 of the frame as shown. Loosely mounted on the outer end of the shaft 14 is a sprocket gear 15 having on the outer side of its hub a clutch member 16 which when the gear is shifted outwardly on the shaft 14 is adapted to be brought into engagement with a clutch member 17 fixed on the outer end of the shaft whereby the 100 105 110

sprocket gear is locked to and driven by the shaft for a purpose hereinafter described.

Fixed on the power transmitting shaft 14 intermediate its ends is a bevel gear pinion 18 which has an operative engagement with a large bevel gear 19 which is revolvably mounted on a short stud shaft 20 arranged on the bar 2 as shown. The gear 19 is provided with a crank pin 21 to which is pivotally connected the upper end of a bundle throwing arm which projects downwardly between and is slidably held in position by two guide rollers 23 which are adjustably mounted in a segmental bar or bracket 24 which is secured to the curved brace 4 of the supporting frame as shown. On the lower end of the arm 22 is a plate 25 having formed thereon forked bundle engaging hooks 26 which are adapted to engage the bundles as they leave the discharging mechanism D of the binder and to throw said bundles over into the carrier of the attachment as will be hereinafter more fully described. The plate 25 is hingedly connected at its inner end to the arm 22 and is held in yielding engagement therewith by a bolt 27 having thereon a coiled spring 28 which is arranged between the plate and the thumb nut 29 on the bolt whereby the pressure of the spring is adjusted to yieldingly hold the plate 25 against the end of the arm and to permit the hooks of the plate to have a yielding engagement with the bundles.

Pivotedly mounted in the depending arm 3 of the frame near its lower end is an eye bolt 30 in the outer end of which is secured the main bar 31 of the bundle carrier 32. The bar 31 is of suitable length and is preferably constructed of gas pipe or similar metal tubing and said bar is connected to the eye bolt nearer the rear end of the bar than the forward end whereby when the bar is released the forward end thereof will overbalance the rear end and cause the bar to swing to a vertical position as will be hereinafter more fully described. The bundle carrier 32 is preferably in the form of a cradle and comprises a series of curved fingers 33 which are spaced apart and secured at their outer ends in the bar 31 as shown. The fingers 33 project inwardly toward the machine and are arranged in parallel position to receive the bundles thrown thereon by the hooks 26 on the end of the bundle throwing arm 22 hereinbefore described. On the shorter end of the bar 31 is an offset bracket 34 the outer end of which is connected to a brace plate 35 which is pivotally connected to the inner end of the eye bolt 30 to which the bar 31 of the carrier is connected. To the opposite end of the bar 31 is secured an offset bracket 36 to which is connected one end of a carrier retracting chain 37 which passes upwardly around a guide pulley 38 revolvably mounted 65 in suitable bearings 39 on a stop plate 40

which is secured to and supported at the front end of the carrier by a suitably braced supporting arm 41 which is connected to and projects forwardly from the arm 3 of the carrier supporting frame. The purpose of the stop plate 40 will be hereinafter described. The chain 37 after passing around the guide pulley 38 extends upwardly and over the sprocket gear 15 which is loosely mounted on the outer end of the power transmitting shaft 14 and from said sprocket gear 15 the chain extends downwardly and has its end connected with a tension rod 42 which is slidably engaged with an apertured guide lug 43 arranged on the bracket 34 secured to the shorter end of the bar 31. The lower end of the tension rod 42 is threaded and has thereon a nut and between said nut and the lug 34 is a coiled spring 44 the pressure of which is exerted to keep the chain 37 taut and to impart the proper tension thereto.

Mounted in a suitable bearing 45 secured to the outer side of the main bar 31 of the carrier is a short crank shaft 46 having on one end an inwardly extending curved bundle engaging arm 47 which projects over the bundles deposited onto the carrier. On the opposite end of the crank shaft 46 is a short crank arm 48 to which is connected a rod 49 which extends upwardly through an apertured guide block 50 secured to the brace 51 of the supporting arm 41. The outer end of the rod 49 is threaded and has screwed thereon a nut 52 between which and the block 50 is arranged a coiled spring 53 the pressure of which is exerted to yieldingly hold the rod 49 so that when a sufficient number of bundles have been deposited onto the carrier and the latter has been released in the manner described and has started to swing downwardly for depositing the bundles in a shock the downward movement of the carrier will cause the crank arm 48 on the shaft 46 to pull against or yieldingly hold the spring retracted rod 49 thereby causing said rod to rock the shaft 46 and swing the bundle gripping arm 47 downwardly against the bundles in the carrier thereby firmly holding said bundles until the carrier has swung downwardly to a position for depositing the bundles on the ground. By this arrangement it will be seen that the bundles will be kept together in the carrier while the latter is being tilted so that all of the bundles are discharged from the carrier at the same time and will remain in a standing position supported by each other in the form of a shock when discharged from the carrier. At a suitable position in the rod 49 is arranged a stop pin 54 which is adapted to engage the guide block 50 through which the rod 49 slides thereby limiting the retracting movement of the rod by the spring 53.

The butts of the bundles when thrown into the carrier come into engagement with the stop plate 40 and by means of said plate the butt ends of the bundles are squared up 5 and they are prevented from falling out of the carrier. When the carrier is swung to a vertical position for discharging the bundles the movement of the carrier is limited by a hook shaped stop 55 arranged 10 on and projecting laterally from the lower end of the arm 3 in the path of movement of the bar 31 of the carrier as shown. Secured to the bar 31 of the carrier on opposite sides of its pivotal connection with the arm 3 is 15 the forked lower end of a carrier holding bar 56 which projects upwardly adjacent to the outer side of the arm 3 and has on its upper end a stop finger 57 on which is revolvably mounted a guide roller 58 which is 20 adapted to travel on a segmental track plate 59 secured to the upper portion of the arm 3 and to the plate supporting arm 41 as shown. By arranging the bar 56 and the roller 58 as herein shown and described it 25 will be seen that when the carrier swings to vertical horizontal positions that the roller 58 will engage and travel on the track plate 59, thus relieving the eye bolt 30 which supports the carrier, from a torsional strain 30 which would be applied thereto by the weight of the load of bundles on the laterally projecting fingers of the carrier. The engagement of the roller 58 with the track plate 59 will also obviate any tendency of 35 the bar 31 to turn in the eye bolt which supports the same.

The carrier is held in a horizontal position to receive the bundles thrown therein from the discharge mechanism of the binder 40 by a detent or stop pin 60 which has a sliding engagement with a transverse aperture in the upper portion of the arm 3 and which is yieldingly projected and held in a projected position by a flat spring 61 secured to the 45 arm 3 and having an operative engagement with a stud 62 on the inner end of the stop pin as shown. By means of the spring 61 the outer end of the stop pin is projected in the path of movement of the stop finger 57 50 on the upper end of the bar 56 thereby holding the carrier in a horizontal position for receiving the bundles discharged from the machine.

In order to retract the stop pin 60 and to 55 thereby permit the carrier to tilt and discharge the bundles carried thereby, I provide an automatically operated pin retracting mechanism comprising a rod 63 which is connected at one end to the inner end of 60 the pin 60 and guided in a bracket 64 on the carrier supporting bar 2 as shown. Adjustably secured to the rod 63 near its inner end is a tappet block 65 which is adapted to be engaged by a tappet stud 66 arranged 65 on and projecting laterally from one side of a ratchet gear 67 which is revolvably mounted in a bearing bracket 68 on the brace 4 of the carrier frame as shown. Loosely mounted on one end of the shaft of the ratchet gear 67 is a lever 69 having 70 thereon a spring pawl 70 which is adapted to engage the teeth of the ratchet gear 67 whereby when the lever 69 is rocked a step by step movement will be imparted to the ratchet gear. The lever 69 is actuated by a 75 rod 71 the upper end of which is adjustably connected to the lever in one of a series of apertures formed therein while the opposite end of said rod is pivotally connected to the outer end of a short crank arm 72 fixed 80 on the shaft of the rotary disk 73 which carries the bundle kicking arm 74 of the bundle discharging mechanism of the binder. By thus connecting the lever with the bundle discharging mechanism it will be 85 seen that at each revolution of the disk 73 the lever will turn the ratchet gear 67 for the distance of one tooth. When the ratchet gear is thus turned to bring the stud 66 thereon into engagement with the block 65 on the pin retracting rod 63, the movement of the latter will retract said stop pin thereby permitting the carrier to tilt and discharge the bundles therefrom in the manner described. By constructing the pin retracting mechanism as herein shown and described it will 90 be seen that by varying the adjustment and relative sizes of the parts or by providing the ratchet gear with two or more tappet studs, the stop pin 60 may be retracted to 95 permit the carrier to tilt at any desired time or when any desired number of bundles have been deposited therein.

After the stop pin 60 has been retracted and the carrier permitted to tilt and discharge the contents thereof the carrier retracting mechanism is automatically thrown into operation to swing the carrier back or to restore the same to its normal position for receiving the next load of bundles. The 105 means for automatically throwing the carrier retracting mechanism into gear comprises a rock shaft 75 which is mounted to turn in suitable bearings 76 arranged on the outer side of the main bar 31 of the carrier. On the inner end of the rock shaft 75 is formed a downwardly and inwardly curved trip arm 77 which projects between two of the bundle supporting fingers of the carrier and which is adapted to be engaged 110 by the bundles thrown onto said fingers. On the outer end of the rock shaft 75 is formed an offset or cam projection 78 which, when the trip arm 77 is released by the discharge of the bundles from the carrier, is 115 adapted to be turned by a torsional spring 79 arranged on and connected at one end with the shaft 75 and at its opposite end with the bar 31. The offset or cam projection 78 when thus turned is brought into 120 125 130

engagement with a plate 80 on the lower end of a gear shifting lever 81 which is pivotally mounted in a supporting bracket on the upper end of the arm 3 and provided with a 5 forked upper end having a loose engagement with the annularly grooved hub of the sprocket gear 15 whereby the latter is shifted outwardly and the clutch member 16 thereon brought into engagement with the 10 clutch member 17 fixed on the shaft 14, thus causing said shaft to turn the sprocket gear 15, thereby moving the chain 37 in the proper direction for swinging the carrier upwardly to a horizontal position.

15 The plate 80 is hingedly connected at its upper end to the clutch shifting lever 81 and has its lower end projecting a slight distance below the lower end of the lever, said lower end of the plate being held in yielding engagement with the lever by a coiled spring 82 arranged on a bolt 83 which projects laterally from the lower end of the lever and through a slot in said plate. The tension of the spring is regulated by a 20 thumb nut 84 on the end of the bolt 83 as shown. When the chain 37 has swung the carrier upwardly to a horizontal position the roller 58 on the stop finger 57 of the bar 56 will be brought into engagement with 25 the inner side of the plate 80 thereby forcing the latter and the lower end of the gear shifting lever 81 outwardly and its upper end inwardly, thus shifting the gear on the shaft 14 and disengaging the clutch member 30 of the gear from the clutch member on the shaft which will thus disconnect the shaft from the gear and immediately stop the 35 operation of the latter.

From the foregoing description taken in 40 connection with the accompanying drawings, the construction and operation of the invention will be readily understood without requiring a more extended explanation.

Various changes in the form, proportion 45 and the minor details of construction may be resorted to without departing from the principle or sacrificing any of the advantages of the invention as claimed.

Having thus described my invention, what 50 I claim is:

1. A shock forming attachment for grain binders comprising a carrier supporting frame suitably secured to the frame of the binder, a carrier pivotally mounted on said 55 frame, a detent, a holding bar on said carrier, a stop finger on said bar to engage said detent and hold said carrier in a horizontal position, means to retract said detent whereby the carrier is permitted to tilt the discharge 60 the bundles thereon, a power transmitting shaft driven by the binder, a gear loosely mounted on said shaft, a clutch mechanism between said gear and shaft, means for automatically closing the clutch 65 when the carrier is swung to a dumping po-

sition, a chain connecting the carrier with said gear, and a roller mounted on said stop finger and adapted to open said clutch when the carrier is brought to a horizontal position.

2. A bundle shocking attachment for grain binders comprising a supporting frame having a depending arm, a bundle carrier comprising a main bar pivotally connected near one end with said arm, a series 70 of fingers projecting from said bar in position to receive the bundles discharged from the binder, a crank shaft mounted on the carrier, a bundle engaging arm on said shaft, a rod connected with the crank of said arm and having a sliding and yielding connection with the support for the carrier whereby when the latter is tilted said bundle engaging arm is pressed into yielding engagement with the bundles, means for dumping 75 the carrier, and means to automatically return the carrier to an operative position.

3. A shock forming attachment for grain binders comprising a carrier supporting frame suitably secured to the frame of the binder, a carrier pivotally mounted on said frame, a detent to hold said carrier in an operative position for receiving the bundles discharged from the machine, a detent retracting mechanism whereby said detent is 80 retracted to permit the carrier to dump, a power transmitting shaft geared to a moving part of the binder, a carrier retracting gear loosely mounted on said shaft and having thereon one member of a clutch, a co-acting clutch member fixed on said shaft, a gear shifting lever engaged with said gear, a spring actuated rock shaft on said carrier, a cam on one end of said shaft, a trip arm 85 on the shaft adapted to be engaged by the bundles in said carrier when the latter is in an operative position and which is released when the carrier is tilted and the bundles discharged, thereby permitting said spring actuated shaft to rock and engage the cam 90 end thereof with said gear shifting lever whereby said gear is shifted into engagement with said fixed clutch member and thereby connected with said power transmitting shaft, a carrier retracting chain having 95 an operative engagement with said gear, means to yieldingly and adjustably connect said chain with said carrier whereby the latter is restored to a horizontal position after being dumped, and means to throw 100 said gear out of engagement with said power transmitting shaft.

4. A shock forming attachment for grain binders comprising a carrier supporting frame suitably secured to the frame of the binder, a carrier pivotally mounted on said frame, a detent, a holding bar on said carrier, a stop finger on said bar to engage said detent and hold said carrier in a horizontal position, means to retract said detent where- 110

- by the carrier is permitted to tilt and discharge the bundles thereon, a power transmitting shaft geared to and driven by a moving part of the binder, a carrier retracting gear loosely mounted on said shaft and having thereon one member of a clutch, a co-acting clutch member fixed on said shaft, a gear shifting lever adapted to be automatically operated when the carrier is 5 swung to a dumping position to shift said gear into engagement with said fixed clutch member whereby the gear is driven by said shaft, a carrier retracting chain connected at its end with said carrier and having an 10 operative engagement with said gear whereby when the latter is driven the carrier will be swung upwardly to an operative position, and a roller revolvably mounted on said stop finger and adapted to be engaged with said 15 gear shifting lever when the carrier is brought to an operative position and to thereby disconnect said gear from said power transmitting shaft.
5. A shock forming mechanism for grain binders comprising a carrier supporting frame secured to a suitable part of the binder, a bundle carrier, a drive shaft geared to a moving part of the binder, a power transmitting shaft geared to said drive shaft, a pinion fixed on said power transmitting shaft, a revolvably mounted bevel gear engaged with and driven by said pinion, a crank pin on said gear, a bundle throwing arm pivotally connected to and 20 operated by said crank pin, adjustably mounted guide rollers adapted to guide said arm, a plate yieldingly secured to the end of said arm and having bundle engaging 25 hooks whereby the bundles are engaged and thrown from the discharging mechanism of the binder into said carrier and means for dumping the latter.
6. A bundle shocking attachment for grain binders comprising a supporting frame secured to the frame of the binder and having 30 a depending arm, an eye bolt pivotally mounted on said arm, a bundle carrier comprising a main bar secured near one end in said eye bolt, a series of curved bundle receiving fingers secured to and projecting 35 from said bar in position to receive the bundles discharged from the machine, a stop plate to receive the butt ends of the bundles when thrown into the carrier, a crank shaft mounted on the carrier, a bundle engaging 40 arm on one end of said shaft, a crank arm on the opposite end thereof, a spring retracted rod connected with said crank arm and having a sliding and yielding connection with the supporting arm of the carrier 45 whereby when the latter is tilted said bundle engaging arm is pressed into yielding engagement with the bundles and the latter thereby held on the carrier until the same has reached a dumping position, means for 50 dumping the carrier, and means to automatically return the carrier to an operative 55 position.
- In testimony whereof I have hereunto set my hand in presence of two subscribing witnesses.
- CHARLES BARNUM.
- Witnesses:
- J. P. COOPER,
M. E. CALLAGHAN.
